(57) **CLAIM**

The ornamental design for a vehicle, as shown and described.

DESCRIPTION

FIG. 1 is a right side view of a vehicle, showing our new design;

FIG. 2 is a left side view of the vehicle;

FIG. 3 is front view of the vehicle;

FIG. 4 is a rear view of the vehicle; and,

FIG. 5 is top view of the vehicle.

The broken lines illustrate portions of the vehicle that form no part of the claimed design.
